UNITED STATES PATENT OFFICE

PETER DELICH, OF DULUTH, MINNESOTA, ASSIGNOR OF THIRTY PER CENT TO
RUDOLPH Z. VOKOVAN, OF DULUTH, MINNESOTA

DESIGN FOR A COMBINATION MIRROR AND RECEPTACLE

Application filed February 12, 1932. Serial No. 42,835. Term of patent 14 years.

To all whom it may concern:

Be it known that I, PETER DELICH, a citizen of the United States, and resident of Duluth, in the county of St. Louis and State of Minnesota, have invented a new, original, and ornamental Design for a Combination Mirror and Receptacle, of which the following is a specification, reference being had to the accompanying drawings, forming part thereof, in which—

I claim:

The ornamental design for a combination mirror and receptacle, as shown.

PETER DELICH.
